HANDBAG

Henry Meyers, Norwalk, Conn.

Application January 20, 1948, Serial No. 3,302

4 Claims. (Cl. 150—34)

1

It is among the objects of this invention to provide a ladies' handbag that is neat, compact, light in weight and simple and inexpensive to manufacture, that provides ample room in a minimum of space for articles normally carried in such handbag and retains such articles so that they may conveniently be removed from the bag. Another object of this invention is to provide a neat and compact insert, having a plurality of superposed pockets thereon, which may readily be applied to the conventional ladies' handbag, that is simple and inexpensive to manufacture and that provides ample room in a minimum of space for retaining those numerous articles to which ready access is desired.

According to the invention these objects are accomplished by the arrangement and combination of elements hereinafter described and particularly recited in the claims.

In the accompanying drawings in which is shown one of various possible embodiments of the several features of the invention,

Fig. 1 is a perspective view of the handbag in open position,

Fig. 2 is a sectional view thereof taken along line 2—2 of Fig. 1.

Fig. 3 is a perspective view of the insert showing the superposed pockets thereon and with parts taken away, and

Fig. 4 is a sectional view of the insert taken along line 4—4 of Fig. 3.

Referring now to the drawings, the particular embodiment of the handbag herein chosen for the illustration of my invention comprises a container 11 of leather, suede, fabric or like material commonly used for ladies' handbags. The container 11 desirably has substantially rectangular side walls 12 and 13 swinging apart and together and pleated end walls 14 and 15, the latter walls each having a V-shaped notch 16 in the upper edge thereof.

An important feature of the present invention is the provision of a plurality of superposed pockets positioned in the container 11 adjacent side wall 12 thereof, and which are to retain those numerous articles to which ready access is desired.

In order to support these pockets an insert or mounting panel 17 is provided. This panel 17 comprises a substantially rectangular stiffening member 18, desirably of cardboard and having a padding or backing 19 of felt, cotton or similar material affixed to the rear wall thereof preferably by stitching.

The front wall of the panel 17 has a facing

2

21 of cloth thereon preferably stitched thereto at the border of the panel 17. Facing 21 lies flush with the upper edge of the panel as at 22 but extends beyond the lateral edges 23 thereof and below the lower edge 24 thereof to form side wings 5 and bottom wing 26 as best shown in Fig. 3.

Illustratively four superposed pockets 28, 29, 30 and 31 are provided on panel 17 in a substantially terraced formation so that each pocket is readily accessible. Pocket 28 is formed from a substantially rectangular sheet 32 of fabric of greater width than that of panel 17. The sheet 32 is folded around a backing liner 33 preferably of cardboard so as to encompass the latter. The folded end 34 of the sheet 32 is affixed to the panel 17 at the lower edge thereof desirably by stitching while each of the lateral edges 35 and 36 of sheet 32 is affixed as by stitching as at 36' to the corresponding lateral edges of the panel 17, thereby forming the pocket 28. Lateral edge 36 of the sheet 32 is folded to form a pleat therein and cardboard stiffening strips 37 and 38 are provided in each of the walls 39 of the pleat between the plies thereof. The lower edges of each of the walls 39 is then stitched as at 41 to the lower edge of the panel 17.

The upper edge 42 of sheet 32 has a tape 43 stitched between the plies thereof, the tape 43 having scoops thereon and forming one half of the "zipper" closure 44.

30 A border 45 desirably of material similar to that of the handbag is stitched at its top and side edges 46 to the panel 17 so as to be flush with the upper edge 22 and side edges 23 thereof. The lower edge 47 of the border which is not stitched 35 to the panel 17 has a tape 48 stitched thereon, the tape 48 having scoops thereon and forming the other half of the "zipper" closure 44. A slide member 49 is provided which coacts with the scoops on tapes 43 and 48 to close and open pocket 28.

As the tapes 43 and 48 lie in substantially the same plane against panel 17, their scoops will be flush against the panel and not protrude beyond the face of the pocket 28, thereby occupying a minimum of space.

Pocket 29 which illustratively has no closing means is superposed on pocket 28 and has pleats 51 at the sides thereof to permit expansion of the pocket when a handkerchief, mirror or other article is placed therein, and stiffening members 29' are provided in each of the pleated sides, creased as at 30' to permit ready collapse of such sides. Pocket 29 is formed from a sheet 52 of fabric reversely folded at its top to form a double

55

ply and is affixed as by stitching as at 53 to the lower edge of sheet 32 and panel 17. The bottom of pocket 29 has a pleat 54 therein and a cardboard stiffening member 55 is provided in said pleated portion 54 to provide rigidity thereto. The bottom corners 56 of sheet 32 have each a substantially square segment removed therefrom so that when the bottom of the pocket and the pleats 51 in the sides thereof are formed there will be no bunching of material at the corners of the pocket 29 when said pleated portions are compressed.

In order to form the pocket 30, nearly the entire top or fold edge of the front wall 57 of pocket 29 is slit as at 58 and the fabric at the ends of the slit are stitched as at 57' to prevent ripping thereof. A "zipper" closure 59 is provided on said top edge to afford a readily accessible change purse which may conveniently be opened and closed. In order to stiffen pocket 30, stiffening members 61 are affixed to the inner walls thereof preferably by gluing.

Affixed to the outer face of pocket 30 is a pocket 31 comprising a substantially rectangular strip 62 of fabric affixed at its bottom edge 63 and at its lateral edges 64 as by stitching to the bottom and lateral edges respectively of the outer face of pocket 30.

Strip 62 is gathered in folds 65 along the length thereof to permit expansion of the pocket 31 in order that it may accommodate a mirror, comb or other articles and an elastic band 66 is provided secured at each end to the respective lateral edges of pocket 30 and concealed in a hem 67 at the top of pocket 31.

The panel 17 with its superposed pockets is positioned in the handbag against side wall 12 thereof.

A pair of substantially U-shaped frames 69 and 70 desirably of metal is provided for the handbag. Frame 69 is affixed to the upper edge 71 of side wall 12 of the handbag and to the top edge 22 of the panel 17 clamping the two edges 71 and 22 rigidly together between the faces 72 and 73 of the frame 69.

The legs 74 and 75 of frame 69 are affixed to the adjacent V-shaped upper edge 16 of the side walls 14 and 15 clamping the upper edges 76 of side flaps 25 of the facing against the upper edges of said side walls.

Frame 70 is affixed to the upper edge 77 of side wall 13 of the handbag, the faces 78 and 79 of the frame clamping said upper edge 77 and the upper edge 81 of a fabric lining 82 rigidly together. The upper ends 83 of a pair of straps 84 are also clamped between said faces 78 and 79, the lower ends 85 of said straps being affixed to a conventional accessory purse 86 to support the latter so that it rests on lining 82.

The legs 87 and 88 of frame 70 are affixed to the adjacent V-shaped upper edge 16 of the side 14 and 15 clamping the associated lateral edges 89 of the lining 82 against the upper edges of said side walls.

The adjacent free edges of the lining 82 and the facing 21 are then stitched together at the bottom of the handbag as at 91 and at the sides thereof as at 92 to complete the assembly.

It is to be noted that frames 69 and 70 are hingedly connected as at 93 at the adjacent ends of legs 74, 87 and 75, 88, respectively, and have a suitable catch 94 at the top thereof to keep the bag closed.

The bag when opened provides free access to the interior thereof and the user, when requiring

any particular item, does not have to search through a jumble of articles at the bottom thereof but may readily locate the article she desires in the convenient and readily accessible pockets provided thereon on panel 17.

The depth of the handbag 11 is such that when the pockets superposed on panel 17 are filled, the bag may still be closed without bulging the sides thereof; thereby resulting in a handbag that is practical, neat and pleasing in appearance.

As many changes could be made in the above construction, and many apparently widely different embodiments of the invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A handbag comprising a container having side walls swinging apart and together, a panel positioned on one of said side walls, said panel comprising a stiffening member having a facing on one side thereof, a pocket on said panel, said pocket comprising a sheet of fabric of greater width than said panel and folded to double ply thickness, a cardboard stiffening liner between said plies, said sheet being affixed at its bottom and lateral edges to said panel and having a pleat near one of the lateral edges thereof, thereby permitting expansion of said pocket, a border affixed to said panel at the upper and lateral edges thereof, the lower edge of said border and the upper edge of said sheet having "zipper" means thereon whereby said pocket may readily be opened and closed, a second pocket superposed on said first pocket and having its mouth extending parallel to the mouth of said first pocket and positioned therebelow, said second pocket comprising a sheet of fabric folded to form a double ply and affixed at its lateral and lower edges to the corresponding edges of said first pocket, said second pocket having pleats at the sides and bottom thereof to permit expansion of said pocket, the front wall of said second pocket having a slit through the folded upper edge thereof to form a third pocket, a "zipper" closure affixed to the slit upper edge of said front wall and a stiffening member affixed to each of the inner walls of said third pocket.

2. A handbag comprising a container having side walls swinging apart and together, a panel positioned on one of said side walls, said panel comprising a stiffening member having a facing on one side thereof, a pocket on said panel, said pocket comprising a sheet of fabric of greater width than said panel and folded to double ply thickness, a cardboard stiffening liner between said plies, said sheet being affixed at its bottom and lateral edges to said panel and having an accordion pleat near one of the lateral edges thereof, thereby permitting expansion of said pocket, a border affixed to said panel at the upper and lateral edges thereof, the lower edge of said border and the upper edge of said sheet having substantially flat "zipper" means thereon whereby said pocket may readily be opened and closed, a second pocket superposed on said first pocket and having its mouth extending parallel to the mouth of said first pocket and positioned therebelow, said second pocket comprising a sheet of fabric folded to form a double ply and affixed at its lateral and lower edges to the corresponding

edges of said first pocket, said second pocket having pleats at the sides and bottom thereof to permit expansion of said pocket, the front wall of said second pocket having a slit through the folded upper edge thereof to form a third pocket, a "zipper" closure affixed to the slit upper edge of said front wall, a stiffening member affixed to each of the inner walls of said third pocket, and a fourth pocket affixed to the outer wall of said third pocket having its mouth extending parallel to the mouth of said first pocket and positioned therebelow, said second pocket, said fourth pocket comprising a substantially rectangular strip of fabric affixed at its bottom and lateral edges to the corresponding edges of said third pocket, said strip being gathered in folds along its length to permit expansion of said fourth pocket.

3. As an article of manufacture, a panel for handbags, said panel comprising a stiffening member having a facing on one side thereof, said facing having wings extending beyond the lateral and bottom edges of said stiffening member, a pocket on said panel, said pocket comprising a sheet of fabric of greater width than said panel and folded to double ply thickness, a cardboard stiffening liner between said plies, said sheet being affixed at its bottom and lateral edges to said panel and having a pleat near one of the lateral edges thereof, thereby permitting expansion of said pocket, a border affixed to said panel at the upper and lateral edges thereof, the lower edge of said border and the upper edge of said sheet having coacting "zipper" means thereon whereby said pocket may readily be opened and closed, a second pocket superposed over said first pocket and having its mouth extending parallel to the mouth of said first pocket and positioned therebelow, said second pocket comprising a sheet of fabric folded to form a double ply and affixed at its lateral and lower edges to the correspond-

ing edges of said first pocket, said second pocket having accordion pleats at the sides and bottom thereof to permit expansion of said pocket, the front wall of said second pocket having a slit through the folded upper edge thereof to form a third pocket having its mouth extending parallel to the mouth of said first pocket and positioned therebelow, said second pocket, a "zipper" closure affixed to the slit upper edge of said front wall, and a stiffening member affixed to each of the inner walls of said third pocket.

4. A handbag comprising a container having side walls swinging apart and together, a panel positioned on one of said side walls, said panel comprising a stiffening member having a facing on one side thereof, a pocket on said panel comprising a sheet of fabric folded to form a double ply and affixed at its lateral and lower edges to the corresponding edges of said panel, said pocket having pleats at the sides and bottom thereof to permit expansion of said pocket, the front wall of said pocket having a slit through the folded upper edge thereof to form another pocket, a "zipper" closure affixed to the slit upper edge of said front wall and a stiffening member affixed to each of the inner walls of said other pocket.
